UNITED STATES PATENT OFFICE

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

LAMP-SOCKET.

1,248,135.

Specification of Letters Patent.

Patented Nov. 27, 1917.

Application filed November 9, 1914. Serial No. 371,081.

To all whom it may concern:

Be it known that I, CHARLES J. KLEIN, a citizen of the United States, residing at Milwaukee, in the county of Milwaukee and 5 State of Wisconsin, have invented new and useful Improvements in Lamp-Sockets, of which the following is a full, clear, concise, and exact description, reference being had to the accompanying drawing, forming a part of this specification.

This invention relates to casings for electrical devices and more particularly to means for interlocking the sections of casings for lamp sockets, pendent switches and 15 the like.

One of the objects of the invention is to provide convenient and efficient means for locking a lamp socket cap and shell against axial separation and relative rotation.

Further objects and advantages will appear hereinafter in connection with the description of the accompanying drawing which shows a typical embodiment of the 25 invention.

In the drawing,

Figure 1 is an elevational view, partially in section, of an electric lamp socket.

Fig. 2 is a bottom view of the casing cap, 30 and

Fig. 3 is a perspective view of the casing shell and cap separated, the latter being partially broken away.

Referring more specifically to the drawing, the casing comprises a cap 1 and a shell 2 designed to telescope together and house a suitable insulating base 3 adapted to carry the electrical conducting parts of the socket or other device. Interlocking 35 means are provided to hold the cap and shell together and also to restrain the same against relative rotation.

As illustrated the cap 1 comprises a dome shaped body portion having a depending 45 rim 4 with an out-turned flange 5, and a collar 6 encircling the rim 4 and held thereon by inturned annular flanges 7 and 7². The collar 6 is thus firmly maintained 50 against removal from the cap but free to rotate thereon. The cap rim 4 is also provided with rectangular slots 8 preferably arranged at diametrically opposite points, and the rotatable collar 6 is provided with similar equi-dimensional slots 9 in its flange

7. As illustrated in Fig. 3, when the collar 6 is rotated to aline the slots 9 and 8 openings are thereby formed to receive shell lugs, as will appear.

The lamp socket shown is provided with a switch mechanism having a double ended 60 push button operating member and to accommodate the push buttons the casing shell 2 has oppositely disposed slots 10 in its upper margin. The edges of these recesses contiguous to the shell edge are out-turned 65 to provide four radial lugs 11 having abrupt lower shoulders 12. The insulating base 3 which carries the switch mechanism is also provided with integral portions 13 located directly above the push buttons and of a 70 dimension to snugly fit between the shell lugs 11 so that the base is anchored against rotation relative to the shell.

Assembly and locking of the parts is effected as follows: The cap ring 6 is positioned to aline the slots 8 and 9 whereupon the shell 2, with its base 3 therein, is turned to aline the lugs 11 with the openings in the cap margin so that the parts may be telescoped together. During this operation it 75 is apparent that the flat outer surfaces of the lugs 11 engage the cut metal edges of the cap rim 4 at the slots 8 so that the shell, and consequently the base 3, is locked 80 against rotation relative to the cap. The 95 collar 6 is then turned until the lower flange 7 moves beneath the lugs 11 and the base projections 13 whereby the flat upper surface of said flange 7 engages the cut metal shoulders 12 of the lugs 11 and holds the 90 shell and the base 3 against axial removal from the cap.

Separation of the parts is obviously effected by rotating the cap collar so that the flange 7 clears the shell lugs 11 whereupon the latter may be withdrawn. It is to be noted that primary positioning of the cap 1 upon the fixture may be effected at any desired relative angle for the operating member of the switch and that thereafter the shell may be readily telescoped and locked by a slight turn of the locking ring 6.

What I claim as new and desire to secure by Letters Patent is:—

1. In combination, a cap and shell to telescope and having portions interlocking upon telescoping thereof to prevent relative ro-

tation therebetween and means on one of said parts rotatable relatively thereto for locking said parts against separation.

2. In combination, a cap and shell to telescope and having portions interlocking upon telescoping thereof to prevent relative rotation therebetween and means on the exterior of one of said parts and rotatable relatively thereto for locking said parts against separation.

3. In combination, a cap and shell to telescope and having shoulders coöperating upon telescoping thereof to lock the same against relative rotation and a member on one of said parts rotatable relatively thereto to lock the same against separation.

4. In combination, a cap and shell to telescope and interlock against rotation, a fixed shoulder on one of said parts and a member on the other of said parts rotatable relatively thereto for engaging said shoulder to lock said parts against separation.

5. In combination, a cap and shell to telescope together, means to lock the same against relative movement in one direction as telescoped, and rotatable means to lock the same against movement in a right angled direction after telescoping.

6. In combination, a cap having a marginal slot, a shell having a shoulder to enter said cap slot and engage an edge wall thereof, and a member on said cap rotatable rela-

tively thereto and having an inturned portion to underlie said cap slot and engage said shell shoulder for supporting the same.

7. In combination, a cap having a marginal slot, an annulus surrounding said cap and having a notch to register with said slot, a shell for telescopic engagement with said cap and having a shoulder to enter the slot in said cap through the notch in said annulus, said annulus being rotatable with respect to said cap to lock said cap and shell against separation.

8. In combination, a cap having a flanged and slotted periphery, an annulus flanged about the periphery of said cap and having a notch to register with the slot therein, a shell for telescopic engagement with said cap and having a shoulder to enter the slot in said cap through the notch in said annulus for engaging the walls of the slot thereby preventing relative rotation of said shell and cap, said annulus being rotatable with respect to said cap to lock said shell and cap against separation.

In witness whereof, I have hereunto subscribed my name in the presence of two witnesses.

CHARLES J. KLEIN.
